UNITED STATES PATENT OFFICE

90,937

DESIGN FOR A PLATE OR OTHER ARTICLE OF HOLLOW-WARE

Ernest T. Beck, Gasthof, Germania, Bregenz,
Austria, assignor to International Silver Com-
pany, Meriden, Conn., a corporation of New
Jersey

Application August 26, 1933. Serial No. 49,109

Term of patent 7 years

To all whom it may concern:

Be it known that I, ERNEST T. BECK, a citizen
of the United States, residing at Gasthof, Ger-
mania, Bregenz, Austria, have invented a new,
original, and ornamental Design for a Plate or
Other Article of Hollow-ware, of which the fol-
lowing is a specification, reference being had to
the accompanying drawing, forming a part
thereof.

Fig. 1 is an enlarged detail view of the border
ornamentation shown in Fig. 2; and

Fig. 2 is a plan view of a plate, showing my
new design, which is to be repeated over the com-
plete border of the plate.

The design is intended to be used on service
plates, sandwich plates and similar articles.

I claim:

The ornamental design for a plate or other
article of hollow-ware, substantially as shown
and described.

ERNEST T. BECK.
